UNITED STATES PATENT OFFICE

WILLIAM E. SPERRY, OF SAN DIEGO, CALIFORNIA

TOY

Application filed May 18, 1931. Serial No. 538,318.

This invention relates to toys, and more particularly to toys of the figured type, the primary object of the invention being to provide a toy having the appearance of a horse or other similar animal, the construction of the toy being such that when propelled, the movements of the toy will simulate the movements of a running animal.

Another object of the invention is to provide means whereby a child seated on the toy may exercise his body by raising and lowering his weight on the seat of the toy, the vertical movement of the body so produced, acting to move the device over the surface on which it is supported.

A still further object of the invention is to provide a construction of this character whereby the device may be readily guided by moving the head of the toy.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Figure 1 is a vertical sectional view through a toy constructed in accordance with the invention.

Figure 2 is a bottom plan view thereof.

Referring to the drawing in detail, the device comprises a frame indicated generally by the reference character 5 and constructed preferably of tubular material or piping.

As shown, the frame extends downwardly from the front horizontal section, at 7 from where it extends rearwardly and provides a support for the bracket 8, that is provided with a bearing to receive the axle 9, to which the wheels 10 that support the toy, are secured. Mounted on the axle 9, is a pinion 11 that meshes with the pinion 12 which in turn

is mounted on the stub shaft 13, extending from the frame.

A transversely disposed bar 14 is mounted on the frame, and provides a foot rest for the child seated on the body portion of the device.

The frame includes a hollow bearing member 15 that provides a bearing for the vertical shaft 16 on which the collar 17 is secured, the collar engaging the lower end of the bearing 15, to support the toy in an upright position.

At the lower end of the vertical shaft 16, is a fork 18 in which the wheel 19 is mounted.

The vertical shaft 16 extends through an enlarged opening 20 formed in the body portion 21 of the toy, so that swinging movement of the body portion 21 with respect to the shaft 16, will be permitted.

Extending into the forward end of the frame 5, is a yieldable bar 22, that is curved and extends rearwardly where it is secured within the body portion 21, at 23.

Extending downwardly from the body portion, and secured to the body portion by the same securing means used to secure the bar 22 to the body portion, is a yieldable actuating bar 24, which is provided with inwardly and downwardly extended fingers 25, that engage between the teeth of the pinion 12, as the actuating bar is forced downwardly, thereby rotating the pinion 12, which in turn transmits rotary movement to the pinion 11 for rotating the axle 9 and wheels 10 mounted thereon.

The lower end of the bar 24 extends forwardly as at 26, so that the initial movement is imparted to the pinion 12, by the inwardly extended end 26 of the bar 24.

An upwardly extended bar 27 forms a part of the frame and acts as a bearing against which the yieldable bar 22 engages. Mounted on the upper end of the vertical shaft 16, is a head 28, which may be turned by the person seated on the toy, to guide the toy.

The reference character 29 designates a seat secured to the body portion, the seat being constructed to simulate a saddle to receive the person using the toy.

From the foregoing it will be seen that due to the construction shown and described, a child seated on the toy may by raising and lowering his weight, cause the pinions 11 and 12 to be rotated, rotating the rear axle and wheels to propel the toy.

The toy is not only amusing to the child operating the toy, but affords exercise to the child.

Having thus described the invention what is claimed is:

1. A device of the class described comprising a frame, a body portion mounted for vertical movement on the frame, a rear axle, wheels secured to the axle, a pinion mounted on the axle to rotate therewith, a pinion mounted on the frame and meshing with the first mentioned pinion, and a yieldable bar connected with the body portion and extending to a position adjacent to the last mentioned pinion to engage the last mentioned pinion to rotate the pinions as the yieldable bar moves downwardly, transmitting rotary movement to the wheels.

2. A device of the class described comprising a frame, a yieldable bar supported on the frame, a body portion secured to the yieldable bar to move vertically, a rear axle, wheels secured to the rear axle to rotate therewith, and means for transforming vertical movement of the body portion into rotary movement for rotating the axle and wheels.

3. A device of the class described comprising a frame, a rear supporting axle, wheels mounted on the axle to rotate therewith, a pinion on the axle, a pinion mounted above the axle and meshing with the first mentioned pinion, a vertically movable body portion, a yieldable bar on the body portion, and means on the bar for engaging the teeth of the last mentioned pinion to rotate the pinions, axle and wheels to propel the device.

4. A device of the class described comprising a frame, an axle mounted on the frame, wheels on the axle to move therewith, a body portion having an enlarged opening, a vertical shaft extending through the enlarged opening and connected with the frame, means for yieldably supporting the body portion on the frame to permit the body portion to move vertically, and means for transmitting movement of the body portion to the rear axle to rotate the axle and wheels to propel the device.

In testimony that I claim the foregoing as my own, I have hereto affixed my signature.

WILLIAM E. SPERRY.
